US0D1085583S

(12) **United States Design Patent** (10) **Patent No.:** **US D1,085,583 S**
(45) **Date of Patent:** **** Jul. 22, 2025**

(54) **DOG BARKING RESTRAINING DEVICE SET**

Assistant Examiner — Kathryn A. Davis

(71) **Applicant:** **Shenzhen Smart Pet Technology Co., Ltd.**, Guangdong (CN)

(57)

CLAIM

(72) **Inventor:** **Yaya Jia**, Guangdong (CN)

The ornamental design for a dog barking restraining device set, as shown and described.

(73) **Assignee:** **Shenzhen Smart Pet Technology Co., Ltd.**, Shenzhen (CN)

(**) **Term:** **15 Years**

(21) **Appl. No.:** **29/888,891**

DESCRIPTION

(22) **Filed:** **Apr. 6, 2023**

FIG. 1 is a perspective view of a dog barking restraining device set consisting of a remote controller and a receiver according to the present application;

(51) **LOC (15) Cl.** 30-99

FIG. 2 is an upper perspective view of a dog barking restraining device set, with the remote controller shown in isolation for clarity of disclosure;

(52) **U.S. Cl.**

FIG. 3 is a lower perspective view of the remote controller of FIG. 2;

USPC **D30/199**

FIG. 4 is a front elevational view of the remote controller of FIG. 2;

(58) **Field of Classification Search**

FIG. 5 is a rear elevational view of the remote controller of FIG. 2;

USPC D30/199, 151-152; D3/207-208, 215; D8/356, 358-360.1; D11/79;

FIG. 6 is a left side elevational view of the remote controller of FIG. 2;

(Continued)

FIG. 7 is a right side elevational view of the remote controller of FIG. 2;

(56) **References Cited**

FIG. 8 is a top plan view of the remote controller of FIG. 2; FIG. 9 is a bottom plan view of the remote controller of FIG. 2;

U.S. PATENT DOCUMENTS

FIG. 10 is an upper perspective view of a dog barking restraining device set, with the receiver shown in isolation for clarity of disclosure;
